Fig. 1

Fig. 2

Fig. 3

Fig. 4

Figure 1 is a front elevational view of a goblet, showing my new design;

Figure 2 is a side elevational view;

Figure 3 is a rear elevational view; and

Figure 4 is a top plan view.

The dominant feature of my design resides in the relief ornamentations suggesting teeth and gums on the face of the goblet, as shown.

I claim:

The ornamental design for a goblet, as shown and described.
